UNITED STATES PATENT OFFICE.

ERNEST C. WILCOX, OF MERIDEN, CONNECTICUT, ASSIGNOR TO THE CONNECTICUT TELEPHONE & ELECTRIC COMPANY, INC., OF MERIDEN, CONNECTICUT, A CORPORATION OF CONNECTICUT.

ELECTRICAL IGNITION APPARATUS.

1,138,522.

Specification of Letters Patent.

Patented May 4, 1915.

Application filed June 18, 1914. Serial No. 845,834.

To all whom it may concern:

Be it known that I, ERNEST C. WILCOX, a citizen of the United States, residing at Meriden, New Haven county, State of Connecticut, have invented certain new and useful Improvements in Electrical Ignition Apparatus, of which the following is a full, clear, and exact description.

My invention relates to an improved apparatus for electrical ignition systems, the object of the invention being to so construct such devices to make them exceedingly compact and reliable, and so likewise as to make the various parts easily accessible for cleaning, replacement or repair.

In the accompanying drawings Figure 1 is a vertical sectional view showing certain parts in elevation. Fig. 2 is a plan view with certain parts removed. Fig. 3 is a plan view with other parts removed.

1 is a rotatable shaft which constitutes the support for the various parts hereafter described.

2—2 are cams on the shaft 1.

25 3 is a housing of cylindrical form having a central passage for the shaft 1 and having an upper and a lower chamber.

4 is a condenser located in the lower chamber and held in place and protected by any 30 suitable means as by a removable plate 5 and a spring ring 6 seated in an annular groove in the inner wall of the lower chamber as shown in Fig. 1.

7—7 are passages in the intermediate partition of the housing 3, to permit a tool to be inserted for the purpose of pushing the condenser out when the plate 5 is removed.

In the upper chamber is located a removable carrier element 8, which element carries 40 the interrupter parts by which the primary circuit is interrupted. This make and break mechanism usually comprises a suitable fixed contact point 9 and a movable contact point 10, the latter being carried by an arm 11 45 hinged at 12 in the carrier 8. This arm also preferably carries an anti-friction roller 13 which is operated by the cams 2—2. The arm 11 is spring pressed as by spring 14 so as to normally press the contact point 10 50 into engagement with the contact point 9. The contact point 9 is electrically connected with a terminal or binding post 15 through the medium of a brush like connecting member 16. The terminal member 15 is carried

by the housing 3 and is suitably insulated 55 therefrom as shown in Fig. 1. In the particular form shown, the contact point 10 is on a grounded circuit through the frame. The inner end of the terminal 15 is provided with a contact head 17 against which 60 the brush 16 may engage when the interrupter carrier 8 is pushed into place. An insulating piece 18 at the base of the head 17 may serve as a key to guarantee the proper positioning of the carrier 8 within 65 the upper chamber of the housing 3. The carrier 8 and interrupter parts are assembled as a unit and in the event it is desirable to do any work on the interrupter parts the carrier 8 may be easily pulled out, 70 that is to say, removed from the housing 3 and may be replaced by a new interrupter unit, or the contact elements of the interrupter may be repaired. The carrier 8 preferably fits friction tight in the housing 3. 75 In the side of the carrier 8 I preferably provide a slot 19 through which a small file may be inserted to smooth and brighten the ends of the contact points 9 and 10.

20 is a cover for the upper end of the 80 housing 3, which cover may have a transparent window 21 to allow of observation of the operation of the contact points.

22 is a distributor housing preferably formed of insulating material and having 85 a chamber therein into which the upper end of the shaft 1 projects, and in which chamber is located a distributor head 23. The distributor head is preferably made of insulating material mounted upon, and so as to 90 turn with, the shaft 1. This distributor head carries a distributor brush 24 for a high tension current, and is spring pressed outwardly so as to engage the distributor terminals 25—25 arranged around the chamber within the distributor housing 22 as shown. These terminals include suitable electrical connecting devices which respectively lead to the destinations of the high tension current.

100 26 is a ground terminal which is in suitable electrical connection with the brush 24.

27 is a spring-washer held in place on the shaft 1 by the cotter pin 28, the function of which is to hold the cap 20 in place when the 105 distributor housing is removed. When the distributor housing is in place, the cap 20 will likewise be held in place, since the dis-

tributer housing is held down in any suitable way, as by spring latches 29-29 which engage abutment studs 30-30 on the housing 3, the latches 29 being carried by the 5 distributor housing.

3^a is an operating arm on the housing 3 by which the operative angle of the timer and distributor parts relatively to the cams 2 may be varied.

10 As will be seen, the various parts may be very quickly put together or taken apart and hence in the event of breakage, any of the parts may be quickly replaced by other parts.

15 A decided advantage is obtained by arranging the interrupter parts as a removable unit since it is these parts most frequently require attention, and by this unit arrangement, in the event of a serious injury, a 20 duplicate unit may be introduced easily and quickly without discarding any of the other parts of the apparatus.

25 The condenser is electrically connected at one side by a brush 31 with the terminal 16 while the other side may be grounded by positive contact on the case or housing. Obviously the invention applies whether the circuits are the grounded or the fully insulated type.

30 What I claim is:

1. In an igniter apparatus, a rotatable shaft, a housing supported thereon, a cam driven by said shaft, an interrupter unit including interrupter parts arranged outside 35 of said cam, said unit being arranged to be bodily applied to and removable from said housing, means for holding said unit in operative position in said housing, and a terminal carried by said housing and insulated

therefrom, and arranged to be electrically 40 connected with one of said interrupted parts.

2. In an igniter apparatus, a rotatable shaft, a housing supported thereon, a cam driven by said shaft, an interrupter unit including interrupter parts arranged outside 45 of said cam, said unit being arranged to be bodily applied to and removable from said housing, means for holding said unit in operative position in said housing, and a terminal carried by said housing and insulated 50 therefrom, and arranged to be electrically connected with one of said interrupter parts, and a distributor element comprising a part carried by said housing and another part 55 detachably carried by said shaft.

3. In an igniter apparatus, a rotatable shaft, a housing supported thereon, a cam driven by said shaft, an interrupter unit including interrupter parts, said unit being arranged to be bodily applied to and removable from said housing, means for holding 60 said unit in operative position in said housing, and a terminal carried by said housing and insulated therefrom, and arranged to be electrically connected with one 65 of said interrupter parts, and a distributor element comprising a part carried by said housing and another part carried by said shaft, and a condenser element in the form of a unit, said distributor unit being arranged to be carried by said housing and being detachable therefrom, with means for 70 electrically connecting said condenser with said terminal.

ERNEST C. WILCOX.
